Primary Examiner — Richard Kearney*Assistant Examiner* — Michael Hoffman(74) *Attorney, Agent, or Firm* — Barnes & Thornburg LLP(57) **CLAIM**

The ornamental design for a mask, as shown and described.

DESCRIPTION

FIG. 1 is a perspective view of a mask showing my new design;

FIG. 2 is a front elevation view of the mask of FIG. 1; FIG. 3 is a rear elevation view of the mask of FIG. 1; FIG. 4 is a left side elevation view of the mask of FIG. 1; FIG. 5 is a right side elevation view of the mask of FIG. 1; FIG. 6 is a top plan view of the mask of FIG. 1; and, FIG. 7 is a bottom plan view of the mask of FIG. 1. In the drawings, the broken lines show portions of the mask and form no part of the claim.
